No. 760,787.

PATENTED MAY 24, 1904.

E. G. HAMILTON.
ELECTRIC MAIL AND PACKAGE CARRYING DEVICE.

APPLICATION FILED JULY 28, 1902.

NO MODEL.

UNITED STATES PATENT OFFICE.

EDWARD G. HAMILTON, OF RICHMOND, INDIANA, ASSIGNOR OF TWO-THIRDS TO JOHN C. HAMILTON AND LEROY E. HAMILTON, OF RICHMOND, INDIANA.

ELECTRIC MAIL AND PACKAGE CARRYING DEVICE.

SPECIFICATION forming part of Letters Patent No. 760,787, dated May 24, 1904.

Application filed July 28, 1902. Serial No. 117,366. (No model.)

To all whom it may concern:

Be it known that I, EDWARD G. HAMILTON, a citizen of the United States, residing in the city of Richmond, in the county of Wayne and State of Indiana, have invented new and useful Improvements in Electric Mail and Package Carrying Devices; and I do hereby declare the following to be a full, clear, and exact description of the invention, such as will enable others skilled in the art to which it appertains to make and use the same.

The invention relates to electric mail and package carrying devices adapted to travel in either direction on and in connection with combined carrying or supporting and current-carrying wires in combination with suitable switches, cut-outs, and terminals.

The invention has for its object the provision of a pair of electric motors adapted to travel in opposite directions and by means of suitable gearings adapted to rotate traction-wheels for the purpose of propelling the mechanism upon track-wires suspended between the points between which the device is intended to operate.

Another object is the provision of an electric mail and package carrying device adapted to travel automatically in either direction upon a pair of track-wires and means for supplying electric power to the motors from said track-wires.

Another object is the provision of an electric mail and package carrying device to be suspended on a pair of track-wires composed of two independent and oppositely-disposed electric motors mounted together, carrying a mail or package receptacle and adapted to operate the device in either direction automatically.

Another object is to provide an electric mail and package carrying device which will be simple in character, compact in form, easily operated and maintained, and by which mail or packages may be transported between predetermined points with certainty and precision.

Another object is the provision of an electric mail and package carrying device to be

operated on a pair of track-wires adapted to be operated in either direction and means for automatically reversing the device at either terminal; and another object is the provision of a new article of manufacture in an electric mail and package carrying device which can be manufactured and sold at a comparatively low price.

Other objects and advantages of my invention will appear from the following specification and from the drawings forming a part thereof.

The invention also consists of other features which are specifically set forth in the claims hereunto appended.

By means of my improvements the movements and operations of the different parts of the device are easily, automatically, and quickly controlled, and the operator is enabled to accomplish the objects sought with certainty and precision and time such movements with exactness without any supervision other than that required to keep the machine in order and deliver mail and packages thereto.

The invention consists in an electric mail and package carrying device embodying certain new and novel features and details of construction and relative disposition of the several parts, as hereinafter particularly set forth, illustrated in the drawings, and incorporated in the claims terminating this specification.

In detail the invention relates to an electric mail and package carrying device substantially as shown in the accompanying drawings, in which—

Figure 1 shows a side elevation of my invention. Fig. 2 shows an end elevation thereof. Fig. 3 is a diagrammatical view of the improvement. Fig. 4 is a detail view showing the switch.

Similar indices denote similar parts throughout the several views.

A represents the platform or carriage, which supports the various mechanisms. On the upper surface of the center of the carriage A is secured the switch B, which is adapted to be operated by the horizontal sliding bar C. The

bar C is adapted to slide in slots provided in the posts D and D' near their upper ends. The center of the bar C is provided with an opening to receive loosely the handle E of the 5 switch-arm F in order that the arm F may be thrown either forward or backward by the lateral movements of the bar C.

G, H, and I represent the three terminals of the switch, with wires J, K, and L, respectively, leading therefrom through the carriage A to various points, as will hereinafter be described.

By the above it will be seen that the wire J may be connected with either of the wires 15 K or L by the movement of the bar C.

M and N represent two oppositely-disposed electric motors with their bases abutting and secured together by the screws O and P. The motors M and N, secured together as shown, 20 are suspended and secured underneath the center of the carriage A by the four hangers Q. Said hangers Q each consists of a perpendicular portion secured at the top in the carriage A and secured to the yokes of the 25 motors by screws a. The shafts b and b' of the armatures of the motors are journaled in the hangers Q between the respective screws a, as shown in Fig. 1. Extending out from each of the hangers Q are the arms Q', Fig. 30 1, the outer ends of which are provided with bearings for the axles R and R'. Said axles R and R' extend across the device underneath the carriage A, as shown in Fig. 2, and their outer ends are provided with concave-face 35 traction-wheels S, which are adapted to revolve on the track-wires, as will hereinafter be explained. Attached to opposite ends of the shafts b and b' are gear-wheels T, and attached to each of the shafts R and R' are 40 larger gear-wheels U, which latter are adapted to mesh with the respective gear-wheels T and be revolved thereby.

The motors M and N should be operatively constructed in any well-known manner and 45 arranged in juxtaposition substantially as shown. The wire K, leading from the terminal H, is connected to the brush of the motor M. The wire L, leading from the terminal I, is connected to the brush of the motor N. 50 The wire J, leading from the terminal G, is connected to one of the traction-wheels S, which wheel and the one traveling on the same wire are insulated from their respective shafts R and R', to which they are permanently secured. The wire c leads from the motor M to the screw P, and the wire d leads from the motor N to the screw P, where the two wires c and d are united by said screw P.

V and X represent the track-wires, the wire 55 60 V being negative and the wire X being positive. The two wires V and X are suspended between two points between which my device is intended to operate. Near each of the terminals of the track-wires I provide bumpers 65 Z to engage the respective ends of the bar C.

For instance, the conditions being as above stated, the switch being arranged to connect the wire J with the wire L, the motor N will be operated to carry the device to the right, and should the switch now be reversed, so 70 that the wire J will be connected with the wire K, the motor N thus being cut out of the circuit, the motor M will be operated to carry the device to the left.

The motors should be inclosed in a suitable 75 jacket Y, as indicated by the dotted lines, extending down from the carriage A around and inclosing the motors to protect them from the weather or dust.

Extending down from the screw P is a stationary hook 2, adapted to engage in the bail 3 of the mail-receptacle 4, or the bail 3 may be connected to the motors direct, if desired. The receptacle 4 is in the form of a scoop with a level bottom and with sides extending 85 upward therefrom at right angles thereto, and the bail 3 is secured to the centers of the sides of the receptacle and extends across from one to the other of the sides. The ends 90 of the receptacle are left open in order to receive an arm provided with a stationary brush (not shown) to push the mail or package from the receptacle, which arm and brush may extend out between and below the track-wires from where they are secured near the battery- 95 terminal.

This invention is also intended to be used in large buildings for transporting mail, packages, or other articles to various parts thereof, or it may be used between two buildings, if 100 desired.

My improvements are perfectly adapted to accomplish the results and objects for which it is intended, and it is evident that changes in and modifications of the construction herein shown and described may be made and that analogous parts may be used to accomplish the same results without departing from the spirit of my invention or sacrificing any of 105 its many advantages.

I wish it understood that I do not dedicate any part of my invention to the public and that I wish adequate and just protection for every feature of the device herein shown and described that is new and useful and which 110 involves invention.

Having now fully shown and described my invention and the best mode for its construction and use to me known at this time, what I claim as new, and desire to secure by Letters Patent of the United States, is—

1. The combination with the track-wires, and the carrying device, provided with wheels adapted to engage said wires, of motors for propelling the said carrying device, means 115 for alternately energizing the said motors including a switch, uprights secured to the said carrying device and being formed in their upper ends with slots, a bar slidably mounted in the openings of the said uprights and be- 120 125 130

ing formed with an opening in which the handle of the said switch is received, the ends of said bar projecting beyond the ends of said device, and means arranged adjacent the said wires for engagement with the ends of said bar whereby the said switch is operated.

2. The combination with the track-wires, of a carrying device provided with wheels adapted to engage said wires, motors for propelling the said device, means for alternately energizing said motors including the switch, means for actuating said switch including the means carried by the car which co-operates

with means arranged adjacent the track-wire at its terminals, the frames of said motors having their ends abutting and secured together by screws, and a stationary hook suspended on one of said screws, substantially as and for the purpose specified.

In testimony whereof I have hereunto signed my name to this specification in the presence of two subscribing witnesses.

EDWARD G. HAMILTON.
